United States Patent Office

Des. 221,444
Patented Aug. 17, 1971

221,444

TABLE

Victor Lukens, 300 E. 51st St., New York, N.Y. 10022

Filed May 27, 1969, Ser. No. 17,382

Term of patent 14 years

Int. Cl. D6—01

U.S. Cl. D33—14

FIG. 1

FIG. 2

FIG. 3

FIG. 4

FIG. 5

FIG. 6

FIG. 1 is a top plan view of a table showing my new design,

FIG. 2 is a side view of the table,

FIG. 3 is a bottom view of the table,

FIG. 4 is a top plan view of the table of FIG. 1 where-
in the top is square rather than round,

FIG. 5 is a view in side elevation of the table of FIG.
4, and

FIG. 6 is a bottom plan view thereof.

I claim:

The ornamental design for a table, substantially as
shown.
